UNITED STATES PATENT OFFICE.

JACK J. SHIPLEY, OF PILOTGROVE, TEXAS, ASSIGNOR OF ONE-HALF TO
E. J. COWART, OF PILOTGROVE, TEXAS.

WAGON-BRAKE RATCHET.

SPECIFICATION forming part of Letters Patent No. 691,670, dated January 21, 1902.

Application filed May 27, 1901. Serial No. 62,007. (No model.)

To all whom it may concern:

Be it known that I, JACK J. SHIPLEY, a citizen of the United States, residing at Pilot-grove, in the county of Grayson and State of Texas, have invented certain new and useful Improvements in Wagon-Brake Ratchets; and I do hereby declare the following to be a full, clear, and exact description of the invention, such as will enable others skilled in the art to which it appertains to make and use the same.

My invention relates to new and useful improvements in wagon-brake ratchets, and has for its object to provide an exceedingly simple and effective apparatus of this description by means of which the brake-shoes may be applied to the wheels of a wagon; and a further object of my invention is to provide for the falling or swinging of the upper portion of the brake-lever out of the way when occasion may require by the load or from other causes.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a front elevation of my invention; Fig. 2, a side elevation, and Fig. 3 a top or plan view of the same.

In carrying out my invention as herein embodied, A represents the side of a wagon-bed, near the front end of which is secured by bolts *a* a segmental section *b*. The ends of this segment are provided with outwardly-bent bars *b'*, that are joined by horizontal bar *b''*. Along a portion of the inner edge of said bar is formed a series of ratchet-teeth *c*.

The brake-lever *B* consists of two metal bars arranged parallel side by side for a part of their length, the lower section being bent inwardly and pivoted to the segment *b*. This lower section is provided with a ratchet-dog *d*, adapted to engage with the teeth *c*, so that when the brake-lever is swung forward in such a manner as to apply the brake-shoes

it may be locked and retained in this position, thereby relieving the operator of the necessity of constantly holding the lever in this position; but when it becomes necessary to release the brake-lever this is accomplished by applying lateral pressure to the upper and handled portion of the brake-lever, when the dog *d* will be disengaged from the teeth *c*, thus freeing the brake-lever and permitting it to be swung in a reverse direction, thereby removing the brake-pressure.

To the inner side of the lower portion of the brake-lever is pivoted in journals *e* a vertical roller *f*.

C is a flat steel spring secured to the side of the wagon-bed and adjusted to press against the vertical roller at any position the brake-lever may be placed, thus retaining said lever in position until moved by the operator.

As previously stated, the brake-lever consists of two metal bars. The upper portion is provided with slots *g*, working loosely over rivets *h h'*. By raising this portion until the lower slot clears the rivet *h'* the handle may be swung either forward or back and entirely out of the way when loading cumbersome articles.

The rod *D*, pivoted to the brake-lever at *i* and passing through guide *E*, may be of any suitable shape to connect with the brake-bars of different makes of wagons.

Having thus fully described my invention, what I claim as new and useful is—

A wagon-brake ratchet consisting of a segmental section with lateral projecting ends carrying a horizontal ratchet-bar, a brake-lever pivoted to said section and provided with a ratchet-dog adapted to engage the teeth in a ratchet-bar, a roller attached to the inner side of said lever, a spring bearing against the said roller for holding the said ratchet-dog on said lever in engagement with the ratchet-teeth, the upper section of brake-lever provided with slots adapting it when slightly raised to be folded in either direction substantially as and for the purpose set forth.

In testimony whereof I affix my signature in presence of two witnesses.

JACK J. SHIPLEY.
